UNITED STATES PATENT OFFICE.

JOHN F. GRACE, OF ARLINGTON, NEW JERSEY, ASSIGNOR TO WORTHINGTON PUMP AND MACHINERY CORPORATION, OF NEW YORK, N. Y., A CORPORATION OF VIRGINIA.

SURFACE CONDENSER.

Application filed August 20, 1926. Serial No. 130,406.

This invention relates to steam condensers and more particularly to condensers of the surface type having divided water circulation to permit the tubes in one section of the condenser to be cleaned while the other section is in operation.

An object of the present invention is to provide an improved air cooler or condenser of a type whereby the air will be effectively cooled when the condenser is operating at full surface or when only one section thereof is in operation.

The invention comprises, a condenser in which the air offtake from the air cooler is baffled so that air crosses the tubes on both sides of the water division diaphragm whereby the air crosses the tubes through which the cold water is circulated whether the water is circulated through both sections or only 20 through one section of the condenser, and in which short circuiting of steam to the air pump is prevented under all operating conditions of the condenser.

With these objects in view, the invention 25 consists in various features of construction and combination of parts, which will be first described in connection with the accompanying drawings, showing a surface condenser of the preferred form embodying the invention 30 and the features forming the invention will be specifically pointed out in the claims.

In the drawings—

Figure 1 is a cross section through a condenser constructed in accordance with the 35 present invention.

Figure 2 is an end elevation of a condenser constructed in accordance with the present invention showing the dividing partition and other features which permit divided water 40 circulation through the condenser.

Fig. 3 is a sectional view of the condenser taken on the line 3—3 of Fig. 1.

Referring more particularly to the drawings, in Figure 2 is illustrated, in end view, 45 a surface condenser in which the interior of the water box 1 is divided vertically by the partition 2 forming a right hand section 3 and a left hand section 4. The cold circulating water has independent circulation 50 through the sections of the condenser, it entering the section 3 through the inlet pipe 5 and passing from the section 3 through the outlet 6, while a separate and distinct inlet 7 and outlet 8 for the circulating water are

provided in connection with the section 4. 55 This construction permits one-half or one section of the condenser to operate while the other half or section is shut down, preferably for purpose of cleaning the tubes or for any other repairs which might be necessary and 60 at such times access to the tubes in the shut down section of the condenser is had through man-holes which are normally closed by the cover plates 20.

In the construction of condensers of this 65 type having divided water circulation, it is desirable to properly cool the air to reduce its volume so as to enable it to be handled by a relatively small pump, to circulate the air across cooled tubes, and as shown in Figure 1 70 of the drawings the air cooling part of the condenser is at its lowest portion, and the air passes transversely across the tubes 9.

To prevent air from being drawn through the air suction pipe 10 without its being properly cooled, or passing over tubes through 75 which the water is circulated, at times when one section of the condenser is shut down, a plurality of baffles 11 are provided which extend across and on each side of the central 80 partition 12 in the condenser 1. The baffles 11 are arranged so that the air passing to the air suction 10 will be directed in a sinuous path across the tubes 9 in the air cooler section 85 of the condenser causing the air to pass across the tubes 9 in both sections 3 and 4 of the condenser to insure its passage over tubes through which the cold water is circulating.

It will be understood that the invention is not to be limited to the specific construction 90 or arrangement of parts shown but that these may be modified widely within the invention defined by the claims.

What is claimed is:

1. In a steam condenser having divided 95 water circulation and an air outlet, means for directing the air in a sinuous path to the air outlet whereby the air will be cooled when the condenser is operating as a whole or only in part.

2. In a steam condenser having an air outlet and divided water circulation whereby the condenser may operate in either one or in both of the sections formed by the division of water circulation, a series of baffles arranged to 100 direct air passing to said outlet through portions of both of said sections.

3. In a steam condenser having an air out-

let and divided water circulation whereby the condenser may operate in either one or in both of the sections formed by the division of water circulation, a series of baffles arranged to direct air passing to said outlet in a sinuous path through portions of both of said sections.

4. In a steam condenser having an air outlet and divided water circulation whereby the condenser may operate in either one or both

of the sections formed by the division of water circulation, a plurality of baffles arranged staggeredly in the condenser and projecting from one section into the other section formed by the division of water circulation whereby air passing to said air outlet will be directed in a sinuous path through portions of both of said sections. 15

In testimony whereof I affix my signature.

JOHN F. GRACE.
